(57) **CLAIM**

We claim the ornamental design for a solar panel assembly, as shown and described.

DESCRIPTION

FIG. 1 is a rear perspective view of a solar panel assembly showing our new invention;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line in the figure drawings is included for the purpose of illustrating unclaimed environment and forms no part of the claimed design.
